DESIGN FOR A COMBINATION DOLL, DRESS- ING TABLE, AND LAUNDRY BAG

Natalie Kropatkin, Bronx County, N. Y.

Application November 9, 1944, Serial No. 116,251

Term of patent 7 years

(Cl. 33—6)

To all whom it may concern:

Be it known that I, Natalie Kropatkin, a citizen of the United States of America, residing at 3957 Gouverneur Avenue, county of Bronx and State of New York, have invented a new, original, and ornamental Design for a Combination Doll, Dressing Table, and Laundry Bag, of which the following is a specification, reference being had to the accompanying drawings, forming part thereof.

Fig. 1 is a front perspective view of a combination doll, dressing table, and laundry bag showing my new design.

Fig. 2 is a rear perspective view thereof.

Fig. 3 is a side perspective view of the article.

I claim:

The ornamental design for a combination doll, dressing table, and laundry bag, substantially as shown.

NATALIE KROPATKIN.
